LOCOMOTIVE DRIFTING CONTROL
MECHANISM

Raymond P. Delano, Jr., Baltimore, Md., assignor
to Franklin Railway Supply Company, Inc.,
New York, N. Y., a corporation of New York

Application March 6, 1944, Serial No. 525,181

6 Claims. (Cl. 121—127)

This invention relates to poppet valve mechanism for locomotives, and especially to control means for the intake valves providing for drifting operation of the locomotive, i. e., that operation which is employed under certain conditions particularly when coasting or "drifting" down a long grade without power. In the arrangement here contemplated, drifting operation provides for holding certain of the valves, preferably the intake valves, in open position so as to prevent the development of substantial differences in pressures in the opposite ends of the cylinder, and especially to avoid such reduced pressure or vacuum conditions as might cause induction of cinders into the cylinder from the smoke box when the exhaust valves open.

In various poppet valve gears heretofore used, the function of drifting has been taken care of in a number of ways, one prior arrangement being the employment of specially formed cams in the cam actuating mechanism for the valves.

The arrangement of the present invention includes means for holding the intermediate or cam follower levers away from the intake cams. More specifically, the arrangement of the invention includes a pair of swinging arms adapted to engage behind the free ends of the intermediate levers for a pair of oppositely disposed intake valves, together with a reciprocating operating device for actuating the swing levers to hold the intake valves open.

It is an object of the invention to provide a construction of the type just referred to, which construction is sturdy and also reliable in operation, the mechanism providing not only for positive actuation of the swinging levers in directions to open the intake valves but also for positive actuation of the levers in the opposite direction, thereby insuring that when the drifting mechanism is not in use the normal functioning of the valves is not interfered with.

The invention also contemplates the provision of guide means for the reciprocating operating member of the drifting mechanism, which guide means are located closely adjacent the point of interengagement between the swinging arms and the reciprocating member, whereby the guide means are positioned to take lateral thrusts which may at times occur, for instance if the drifting mechanism is operated at a time when one intake valve of the pair is being held open by its associated intermediate lever.

The foregoing and other objects and advantages are brought out more fully herebelow in

the description of the preferred embodiment of the invention which is illustrated in the accompanying drawings. In the drawings—

Figure 1 is a transverse sectional view through a cam box incorporating valve operating parts to which the invention has been applied;

Figure 2 is a transverse sectional view taken as indicated by the line 2—2 on Figure 1;

Figure 3 is a fragmentary view similar to Figure 2 but with certain parts in a different position; and

Figure 4 is a detail view of one of the parts.

Referring to the drawings, the cam box is indicated at 3, this box being adapted to be mounted above a cylinder and intermediate the valve chests at the ends of the cylinder, in the manner disclosed in copending application of Julius Kirchhof and Raymond P. Delano, Jr., Serial No. 525,180 filed concurrently herewith. Tappets 4 and 5 project from the side walls of the box, fore and aft, to cooperate with the stems of the intake valves in the valve chests, the valve parts not being herein illustrated since they form no part of the present invention per se. These tappets are arranged to be actuated by intermediate levers 6 and 7 which are pivoted in the cam box at 8 and 9, the levers carrying cam rollers 10 and 11 which ride on the cam 12 mounted on cam shaft 13. The poppet valves, as is customary, are provided with return springs for effecting closing movement, and these springs, as is well understood in the art, act through the tappets 4 and 5 and thereby maintain the cam rollers 10 and 11 in contact with the cam surface.

35 The cam employed may either be of an oscillating type or of a rotating type and may be variously shaped, depending upon the particular mechanism, the type or shape of the cam not being of importance from the standpoint of the present invention. It may be mentioned, however, that the invention is particularly adaptable to an arrangement in which the cam is of the rotating type, the cam shaft being axially shiftable in order to control the cutoff and to reverse the operation of the engine, in the manner more fully set out in the copending application above mentioned. In a mechanism of this type in which the cam shaft is axially shiftable, the control 45 means therefor may include a rotatable screw such as indicated at 14 in Fig. 1, which screw cooperates with a traveling nut 15, a connection being made between the nut 15 and the cam shaft 50 in a manner disclosed in said copending application, but which need not be considered here.

Note, however, that the screw 14 is formed on a shaft 16 which, as seen in Figures 1 and 2, extends along the cam box above the cam shaft 13 and the intermediate levers 6 and 7. The drifting mechanism is also situated in this same region and is arranged to straddle and thus accommodate the shaft 16, as will further appear.

Above each of the intermediate levers 6 and 7, a swinging arm 17 is pivotally mounted on a fixed part 18 by pivots 18a, the lower end of this arm being adapted to engage behind the upper end of one of the intermediate levers. Thus, it will be seen that at the right hand side of Fig. 2, outward swinging movement of arm 17 will abut the upper end of intermediate lever 6 and thus move this lever and the associated tappet 4 outwardly, thereby lifting the cam roll 10 from the cam and resulting in opening of the intake valve at the corresponding end of the cylinder. This outward swinging movement of arm 17 is effected by the mechanism described just below.

Toward the top of the cam box a cylinder 19 is arranged, a piston 20 being vertically movable in the cylinder under the influence of pressure fluid introduced through port 21 (see Figure 1). When this piston moves downwardly it engages the upper end of the shaft 22 which projects downwardly and terminates in a double yoke 23—23, the central aperture in each part of the yoke being arranged to accommodate the control shaft 16 of the reversing and cutoff control mechanism.

A pair of pins 24 and 25 are carried between the lower ends of the two parts of the yoke and these pins cooperate with the swinging arms 17 to effect movement thereof.

Each arm 17 has a surface 26 appropriately inclined with respect to the vertical motion of the yoke 23—23 so as to cause the arm 17 to swing outwardly upon downward movement of the cooperating pin 24 (or 25). This causes the opening of the intake valves as above mentioned.

Upward movement of yoke 23—23 and of the actuating piston 20 and the associated parts is brought about (upon exhaust of pressure through port 21) by means of a compression spring 27 reacting between a fixed abutment 28 and an abutment ring 29 which is fixed to the upper end of shaft 22.

When the pins 24 are returned to the upper position, they engage projections 30 which are so shaped as to positively move the swinging arms inwardly away from the upper ends of the intermediate levers 6 and 7.

With respect to the mechanism above described, attention is now called to the fact that the fixed parts 18—18 at opposite sides of the vertically movable yoke members 23 serve as guides for the vertical movement of the yoke members, these guides being extended downwardly to the region of the pins 24 and 25. The guides thus serve to take lateral thrusts which may arise at certain times, for instance when the drifting mechanism is actuated at a time when one valve is closed and the opposite valve is being held open by its associated intermediate lever.

It may also be mentioned that the arrangement described is quite compact and provides for extension of the swinging arms in between the upper ends of the intermediate levers, notwithstanding the fact that the free ends of the intermediate levers are relatively close to each other when both of the intake valves are closed. It is also of advantage that the pins 24 and 25 are tied together by the lower portion of the yokes 23 which lie below the shaft 16.

It will be observed that the arrangement also avoids vibration, chatter and wear because of the fact that the return spring 27 moves the yoke upwardly and the pins 24 and 25 thus swing the arms 17 inwardly or toward each other until they interengage. Parts of the arms 17 themselves thus constitute limiting stops for the upward movement effected by the return spring 27.

It may also be mentioned that with surfaces such as indicated at 26 inclined in the manner described above, a very powerful valve opening force may be derived even from a relatively low pressure introduced above the actuating piston 20. This assures positive action in operation of the mechanism.

The control for the fluid pressure employed to actuate the operating piston 20 may be arranged in any desired manner.

25 I claim:

1. In steam distributing valve mechanism for a locomotive having cam actuated poppet valves, mechanism for opening a valve to provide for drifting operation, including a swinging arm adapted in one position to hold the valve open

30 and in another position to release the valve for normal cam actuation, a reciprocable operating member, and an abutment carried by said member and adapted to bear against a surface of the arm which is inclined in a direction to move the arm to valve-open position.

2. A construction in accordance with claim 1 and further including guide means for the reciprocable member adapted to cooperate therewith in a region adjacent the abutment for moving the swinging arm.

3. A construction in accordance with claim 1 in which the swinging arm further has another surface with which the abutment cooperates upon release movement to positively maintain the swinging arm in its released position.

4. A construction in accordance with claim 1 in which the valve actuating mechanism incorporates an intermediate lever and in which the swinging arm is adapted to engage behind the free end of the intermediate lever to effect opening movement of the valve.

5. In steam distributing valve mechanism for a locomotive having cam actuated poppet valves, mechanism for opening a valve to provide for drifting operation, including a reciprocable operating member, and an arm mounted to swing in a direction generally transverse the path of reciprocation of the operating member and adapted in one position to hold the valve open and in another position to release the valve for normal cam actuation, said arm and said member being interconnected by means of a pin and slot connection providing for positive actuation of the swinging arm in both directions between said positions thereof.

6. A construction in accordance with claim 5 and further including a spring normally urging said reciprocable member to the position corresponding to release of the valve.

RAYMOND P. DELANO, JR.
